UNITED STATES PATENT OFFICE.

HIRAM B. CANNON, OF METUCHEN, NEW JERSEY.

FURNACE OR OVEN.

Application filed May 14, 1924. Serial No. 713,188.

To all whom it may concern:

Be it known that I, HIRAM B. CANNON, a citizen of the United States, residing at Metuchen, in the county of Middlesex and 5 State of New Jersey, have invented a certain new and useful Improvement in Furnaces or Ovens, of which the following is a full, clear, and exact description, reference being had to the accompanying drawings.

10 This invention relates to furnaces or ovens, and more particularly to furnaces of the general type exemplified in my Patent No. 1,371,774, issued March 21, 1921.

15 It is the general purpose and object of the invention to provide a furnace wherein articles or objects are efficiently heated by radiant heat from a combustion chamber of high heat-radiating qualities as well as by sensible heat from the products of combustion 20 and by radiant heat from the floor of the furnace. Further and more limited objects of the invention will appear hereinafter in the detailed description of the invention which follows.

25 In the drawings, which illustrate my invention in one embodiment thereof, Fig. 1 represents a central longitudinal vertical sectional view through a furnace or oven constructed in accordance with such invention; Fig. 2 a transverse sectional view of the furnace or oven shown in Fig. 1, the view corresponding to the line 2—2 of Fig. 1; and Fig. 3 a detail in section corresponding to the line 3—3 of Fig. 2.

30 In the particular embodiment of my invention shown herein, there is illustrated only the construction of the furnace or oven and the cooperating construction and arrangement of the combustion chamber, the 40 space within the furnace or oven and above the combustion chamber and the floor thereof being unoccupied, such space being adapted for the reception of any articles or objects desired to be subjected to the action 45 of the furnace or oven.

Describing the various parts by reference characters, 1 denotes the foundation of the furnace or oven, 2 the front wall, 3 the rear wall, 4 the side walls, and 5 the top wall or roof, the last mentioned wall being provided with an outlet 6 and a flue 7 leading to a stack (not shown). The parts 1-5 inclusive will be made of any approved refractory material of suitable heat-resistant qualities. The base or foundation 1 is of sufficient depth to have formed therewithin

and below the floor 8 of the heating chamber 9 a suitable number of longitudinally extending flues, two of such flues being indicated at 10 and located one on each side of the central portion of the foundation. 60 These flues extend nearly the full length of the furnace or oven, from front to rear thereof, and the floor above such flues is provided with a suitable number of openings 11 for the discharge of products of combustion into the chamber 9. The front ends of the flues 10 are connected by a transverse flue 12, also located below the floor.

65 Supported upon the central portion of the floor, between the flues 10, is a combustion chamber, the said chamber being made of material having high heat-radiating qualities, such as silicon carbide, and comprising generally a bottom wall 13, side walls 14, a top wall or cover 15, a rear wall 16, and a partition 17 extending from the front of the chamber rearwardly toward but spaced from the rear wall 16, thereby to provide an upper passage A, a lower 70 passage B, and an end passage C within the 75 said chamber. The combustion chamber, being formed of silicon carbide will be made of slabs of this material, the joints between adjacent slabs being closed by cement, preferably of silicon carbide. The rear wall 16 80 abuts against and is supported by a stabilizing pier 18 at the rear of the furnace or oven, while the upper passage A is extended in the form of a neck 19 into an opening 20 formed in the front of the furnace or oven. At its front end, the passage B discharges into the front transverse flue 12 through an outlet B'.

85 The combustion chamber shown and described herein may be heated in any approved manner, an oil burner of any approved and standard construction for this purpose being indicated conventionally at 21.

90 With the parts constructed and arranged as described, the operation will be as follows: A combustible mixture being supplied to and burning within the combustion chamber will, under proper manipulation of the fuel and air, extend as a flame from near the burner 21 to the delivery opening B' 95 at the front of the passage B. To enable the operator to regulate this flow of air and fuel so as to produce this result, the front wall is provided with a sight tube 22 having the outer end sealed by mica or other 100 suitable transparent closure 23. With this

regulation of fuel and air, the combustion chamber will be heated in the most efficient manner and, because of its construction and of the material of which it is composed, will deliver heat by radiation in a most effective manner to the chamber 9. The division of the combustion chamber into the upper and lower passages A and B communicating by the passage C beyond the 5 end of the partition 17 provides in effect a long combustion chamber, wherein the combustion in the upper passage A is facilitated by the heat radiated thereinto from the lower passage B through the partition 10 17. The products of combustion delivered from the outlet B' into the flue 12 will be distributed thereby into the flues 10, the arrangement of the openings 11 being such as to ensure practically uniform distribution 15 of these products into the chamber 9 thereabove.

Because of the construction and arrangement of the parts shown herein, articles within the chamber 9 will be heated in a 20 very efficient manner, not only by radiant heat from the combustion chamber and from the floor 8 above the flues 10, but also by the sensible heat contained in the products of combustion delivered through the 25 apertures 11.

Various uses of my furnace or oven will suggest themselves to those skilled in the art. For instance, it is particularly well adapted for use as a core oven; for the 30 heating and distribution of fluid in coils or stills; and for the heat treatment of metal; and I do not propose to limit the use of my furnace or oven to the heating of any particular object or material.

Having thus described my invention, 40 what I claim is:—

1. A furnace or oven comprising in combination walls forming a heating chamber, the bottom wall constituting a floor for said 45 chamber and being provided with a flue beneath said floor, a combustion chamber within the heating chamber and arranged to heat the same by radiation, means for heating the said combustion chamber interiorly, and means for discharging the 50 products of combustion from the combustion chamber into said flue, the said flue being provided with one or more openings for delivering the products of combustion 55 into the heating chamber whereby the said chamber is heated by radiant heat from the combustion chamber and from the floor and by the sensible heat of the gases delivered through the opening or openings in said 60 flue.

2. A furnace or oven comprising in combination walls enclosing a heating chamber, the bottom wall constituting a floor for said 65 chamber and being provided with flues therebeneath, a combustion chamber within

the chamber arranged to heat such chamber by radiation, and means for heating the said combustion chamber interiorly, the said combustion chamber having an outlet for delivering products of combustion to the 70 said flues and the said flues being arranged to deliver such products substantially uniformly to the heating chamber.

3. A furnace or oven comprising in combination walls enclosing a heating chamber, 75 the bottom wall constituting a floor for said chamber and being provided with flues therebeneath and extending longitudinally thereof, a combustion chamber within the heating chamber arranged to heat such 80 chamber by radiation, and means for heating the said combustion chamber interiorly, the said combustion chamber having an outlet for delivering products of combustion to the 85 said flues and the said flues being arranged to distribute such products substantially uniformly to the heating chamber.

4. A furnace or oven comprising in combination walls enclosing a heating chamber, 90 the bottom wall constituting a floor for said chamber and being provided with a flue therebeneath and extending substantially the length thereof, a combustion chamber within the heating chamber and arranged 95 to heat such chamber by radiation and having an outlet for products of combustion discharging into said flue, and means for supplying a combustible mixture to the combustion chamber, the said flue having means 100 for distributing the products of combustion therefrom into the heating chamber.

5. A furnace or oven comprising in combination walls enclosing a heating chamber, the bottom wall constituting a floor for said 105 chamber and being provided with a flue therebeneath, a combustion chamber arranged within the heating chamber and arranged to heat such chamber by radiation and having an outlet for products of combustion 110 discharging into said flue, and means for supplying a combustible mixture to the combustion chamber, the said flue extending substantially the full length of the first mentioned chamber and being provided with discharge openings arranged substantially equidistantly apart whereby the products of combustion will be distributed substantially uniformly to the heating 115 chamber.

6. A furnace or oven comprising in combination walls enclosing a heating chamber, the bottom wall forming a floor for said chamber and being provided beneath said floor with laterally spaced flues extending 120 from the front portion thereof toward the rear portion thereof and with a transverse flue adjacent the front thereof communicating with the first mentioned flues, a combustion chamber supported within the heating 125 chamber between the first mentioned 130

- flues and extending longitudinally of such heating chamber, the said combustion chamber having a partition intermediate the top and bottom thereof and extending from the 5 front toward but spaced from the rear thereof and forming upper and lower communicating passages within such combustion chamber, the front of the lower passage communicating with the transverse flue, and 10 means for supplying a combustible mixture to the front of the upper passage, the said combustion chamber being composed of material having high heat radiating qualities, and the first mentioned flues being provided 15 each with one or more openings for delivering products of combustion supplied thereto into the first mentioned chamber.
7. A furnace or oven comprising in combination walls enclosing a heating chamber, 20 the bottom wall forming a floor for said chamber and being provided beneath said floor with laterally spaced flues extending from the front portion thereof toward the rear portion thereof and with a transverse 25 flue adjacent the front thereof communicating with the first mentioned flues, a combustion chamber supported within the first mentioned chamber between the first mentioned flues and extending longitudinally of 30 such heating chamber, the said combustion chamber having a partition intermediate the top and bottom thereof and extending from the front toward but spaced from the rear thereof and forming upper and lower 35 communicating passages within such combustion chamber, the front of the lower passage communicating with the transverse flue, and means for supplying a combustible mixture to the front of the upper passage, 40 the said combustion chamber being composed of material having high heat radiating qualities and the first mentioned flues being provided with openings for delivering products of combustion supplied thereto 45 into the first mentioned chamber, the said openings being arranged to distribute the products of combustion substantially uniformly throughout the length of their respective flues into the chamber thereabove.
8. A furnace or oven comprising in com-
- binatiion walls enclosing a heating chamber, the bottom wall forming a floor for said chamber and being provided beneath said floor with laterally spaced flues extending from the front portion thereof toward the 53 rear portion thereof and with a transverse flue communicating with the first mentioned flues, a combustion chamber supported within the heating chamber and extending longitudinally of such chamber, the said 60 combustion chamber having an outlet communicating with the transverse flue, and means for supplying a combustible mixture to the combustion chamber, the said combustion chamber being composed of material having high-heat radiating qualities, and the first mentioned flues being provided each with one or more openings for delivering products of combustion supplied thereto into the first mentioned chamber. 70
9. A furnace or oven comprising in combination walls enclosing a heating chamber, the bottom wall forming a floor for said chamber and being provided beneath said floor with laterally spaced flues extending 75 from the front portion thereof toward the rear portion thereof and with a transverse flue communicating with the first mentioned flues, a combustion chamber supported within the first mentioned chamber between the 80 first mentioned flues and extending longitudinally of such first mentioned chamber, the said combustion chamber having an outlet communicating with the transverse flue, and means for supplying a combustible mixture 85 to the combustion chamber, the said combustion chamber being composed of material having high heat-radiating qualities and the first mentioned flues being provided with openings for delivering products 90 of combustion supplied thereto into the first mentioned chamber, the said openings being arranged to distribute the products of combustion substantially uniformly 95 throughout the length of their respective flues into the chamber thereabove.

In testimony whereof, I hereunto affix my signature.

HIRAM B. CANNON.
